ARTHUR S. HUGHES AND HOWARD F. GORSUCH, OF MANSFIELD, OHIO, ASSIGNORS TO THE HUGHES-KEENAN COMPANY, OF MANSFIELD, OHIO, A CORPORATION OF OHIO.

DUMPING TRUCK

Application filed September 7, 1927. Serial No. 218,034.

This invention relates to dumping trucks, and among other objects, aims to provide improved mechanism for initiating the dumping movement of the body.

5 This is a companion application to the application recently filed by us, Serial No. 215,714. This present invention is an improvement on the mechanism described and claimed in the pending application of Arthur 10 S. Hughes, Serial No. 739,803.

In the accompanying drawings showing a preferred embodiment of the invention:

Fig. 1 is a sectional elevation of mechanism of the character described, interposed between and connected to the lower portion of a dumping body and its frame or chassis, fragments only of the body and frame being shown, and the parts being in latched position;

20 Fig. 2 is a similar view, but showing the parts unlatched and the body moved partly toward dumping position;

Fig. 3 is a cross section, looking toward the front, showing particularly the latch and 25 operating rod; and

Fig. 4 is a view like Fig. 3 but showing the strike plates and omitting the latch.

Referring specifically to the drawings, there is shown a portion of a dump body 5, 30 which may be of various types but preferably dumps to the rear. For convenience in description, the body 5 will be assumed to be of this type, although the invention is applicable to bodies dumping otherwise. The 35 supporting frame 6 may be the vehicle chassis, or a separate frame secured upon the chassis proper, and in either case provides a support for the dump body, whose forward end rises and rear end descends in the dumping operation. The rear portion of the body 40 5 is supported on frame 6 either by rockers, as disclosed in said Hughes application, or by rollers as disclosed, for example, in the companion application referred to above.

45 The latching mechanism, by which the body is held down, in material conveying position, consists of a keeper 7, secured to the body, a latch 8 carried on the frame 6, and an operating rod or rock shaft 9, which may be 50 moved by a hand lever (not shown, but dis-

closed in the companion application). Conveniently, the keeper 7 is mounted on an angle 10 secured to the bottom of body 5 and extending crosswise thereof. Latch 8 is shown as freely pivoted on rock shaft 9, 55 which is rockable on its axis to move a latch releasing arm 11 rigidly secured to the rock shaft and engaging a lug 12 on the latch. Bearings 13 on strike plate 14 are provided for rock shaft 9. 60

The strike plate 14 is carried by the frame 6, preferably on a transverse angle 15, along which rock shaft 9 extends from one side of the vehicle, as indicated in Fig. 3. Cooperating with strike plate 14 is a similar plate 65 16 secured to the body at such a point that the two plates meet whenever the body is restored to its normal position.

To prevent disalignment of the body due to play developing in the rear supports, the 70 strike plates have engaging surfaces (Fig. 4) which are so shaped that they center the body each time it falls. This centering prevents undue strain on certain parts connecting the body and frame, as will be understood. 75

To hold the latch in engagement with its keeper, a spring 17 may connect an arm 18 of the latch with some part of the frame, as the angle 15. As the latch rocks independently of the rock shaft 9, the spring will cause it to engage the keeper each time the body moves to the position of Fig. 1. To retract the latch, the rock shaft 9 is moved clockwise as viewed in Fig. 1. 80

The body 5 is preferably so mounted and so loaded that its center of gravity when loaded is located rearwardly of the fulcrum on which the body rocks, so that it will move to dumping position without the application of power, when released from the latch. Sometimes the load cannot be placed just right, or is of a nature which prevents its concentration toward the rear of the body, in which cases the body may have no tendency to dump even when released. Hence it is desirable to provide means to give an impetus to the body to move toward dumping position. As shown, there is a swinging arm 19 fixed to the rock shaft 9 so as to be moved clockwise 85 or toward the body whenever said rock shaft 90 95 100

releases the latch. The swinging arm 19 may directly engage the truck body, or, as shown, to eliminate friction and wear, may engage a roller 20 carried on angle 10 in the path 5 of the swinging arm. Thus rocking of shaft 9 not only releases the body, but positively moves it through a sufficient angle to insure dumping.

As dumping depends largely on distribution of load, and as the body is so poised on its supports that it tends to return to the horizontal position when empty, it follows that during dumping, when the load shifts longitudinally of the body, the body has a 10 tendency to fall before all the load is out of it. To prevent premature return of the body, a "stiff-leg" or toggle lock is provided, said toggle lock comprising, in this instance, two links 21, 22 movable into and out of alignment between their respective pivotal connections 23, 24 with the body and frame. The links 21, 22 may be connected by means of a simple pivot, as is customary in such linkages; but we prefer to provide a "lost-motion" connection with a shock-absorbing member, to take the shock of stopping the body at the end of its dumping movement. As shown, link 21 has a slot 25 at its end and link 22 has a pin 26 slidable in said slot. 15 A coil spring 27 connects link 21 near its slot with the frame, and is so arranged that it is expanded when the links are longitudinally aligned, as occurs whenever the truck is dumped. The momentum of the body 5 at 20 the end of the dumping movement will momentarily expand the spring as the links separate to the greatest extent permitted by slot 25 and pin 26; then the tension of the spring will cause pin 26 to return to the upper end 25 of the slot, where it will remain as long as the toggle is unbroken. Thus undue strain on the pivots of links 21, 22 is obviated.

It is advantageous to provide for adjustment of the latching mechanism. In the 45 present instance, the keeper 7 is adjustable as best shown in Fig. 3, being slotted as at 28 and clamped by bolts 29 passing through angle 10. To prevent change in the adjustment, the keeper is held by a pair of bolts 50 30 which are locked upon the strike plate 16 by nuts. Conveniently, the strike plate 16 has ears 31 through which bolts 30 pass, and the keeper has aligned ears 32 for the same bolts. Thus continual striking of the keeper against 55 the latch cannot shift the keeper and thus make the latch inoperative. At the same time, adjustment is always possible.

To prevent movement of the body lifting 60 arm 19 too far underneath the body, a projection or stop 33 is provided. This stop is shown in Fig. 3 as being carried by the link 22. This arrangement is advantageous, because when the links straighten out to lock 65 the body, the stop 33 will throw arm 19 to

the left, or counter-clockwise, out of the way when the body descends. Thus the end of arm 19 cannot foul with the keeper 7 or the plate 16 or become stuck under the framing of the body. This motion of arm 19 will also restore the rock shaft 9 and all parts actuated therewith to their initial positions (Fig. 1), as arm 19 is rigid with shaft 9.

Obviously the present invention is not restricted to the particular embodiment thereof herein shown and described.

What we claim is:

1. The combination with a dumping body and a frame, of a latch mechanism to hold the body close to the frame; means for releasing the latch; a swinging arm moved upon release of the latch to engage with the body to lift the same; a toggle lock interposed between the body and frame; and a projection on one member of the toggle lock and in the path of movement of the swinging arm; the parts being so disposed that as the toggle lock straightens out, the swinging arm is moved out of the way and is held from assuming a position which would interfere with descent of the body.

2. In combination, a tiltable dumping body; a chassis; a pair of links pivoted to each other and to the dumping body and chassis, respectively; an arm pivoted on the chassis and actuated by the operator to lift the free end of the body through a small arc to initiate dumping movement thereof; and a projection on the link which is pivoted to the chassis, said projection being in the path of said pivoted arm and engaging said pivoted arm as the links straighten out during elevation of the free end of the body, and pushing said pivoted arm out of the way of the body so that descent of the body is not prevented by the upper free end of said pivoted arm.

3. The combination with a dumping body and a frame, of a latch mechanism to hold the body close to the frame; means for releasing the latch; a swinging arm moved by said latch-releasing means to engage with the body to lift the same; and means mounted on the frame and actuated by tilting of the body for causing the swinging arm to move out of the way of the body so that descent of the body is not interfered with.

4. The combination with a dumping body and a frame, of a latch mechanism to hold the body close to the frame; means for releasing the latch; a swinging arm moved upon release of the latch to engage with the body to lift the same; means connected to the body and to the frame to stop movement of the body during dumping; and means on said body-stopping means and engaging the swinging arm when the body dumps to move the swinging arm entirely out of the way of the body, thereby to obviate fouling of the

swinging arm with the body or with some part carried by the body.

5. In combination, a dumping body; a frame for the body; a spring actuated latch; a keeper on the body for engagement with said latch; a manually operable rock shaft carried by the frame; the latch being freely rockable on the rock shaft; means on the rock shaft for engaging the latch when the rock shaft is moved in one direction to release the latch from the keeper; the latch being returned by its spring when said latch-engaging means is released; an arm fast to the rock shaft and engaging under the body when the latch is released to start the body upwardly to dumping position; and means carried by the frame and actuated upon tilting of the body to move the arm out of the way of the body so that descent of the body is not interfered with.

20 In testimony, that we claim the foregoing as our own, we have hereto affixed our signatures.

ARTHUR S. HUGHES.
HOWARD F. GORSUCH.
